PEDESTAL TABLE

Bruce O. Sheppard, 1632 Magnolia Drive, Lancaster, Pa.

Filed Apr. 15, 1960, Ser. No. 60,199

Term of patent 3½ years

(Cl. D33—14)

FIG. 1.

FIG. 2.

FIG. 3.

FIG. 4.

FIG. 5.

Figure 1 is an elevational view of a pedestal table showing my design;

Figure 2 is an elevational view taken at a 90 degree angle to Figure 1;

Figure 3 is a top plan view of the table;

Figure 4 is a bottom plan view thereof; and

Figure 5 is a perspective view viewed from the bottom. I claim:

The ornamental design for a pedestal table, as shown.
